UNITED STATES PATENT OFFICE

RICHARD M. HOLLINGSHEAD, OF CAMDEN, NEW JERSEY.

SCREW-CAP.

No. 897,621.

Specification of Letters Patent.

Patented Sept. 1, 1908.

Application filed August 2, 1907. Serial No. 386,747.

To all whom it may concern:

Be it known that I, RICHARD M. HOLLINGSHEAD, a citizen of the United States, residing in the city and county of Camden, State of New Jersey, have invented a new and useful Screw-Cap, of which the following is a specification.

My invention consists of a screw cap for a can, bottle, or other receptacle, the same being provided with a washer or gasket within the same, and means for seating said gasket and causing it to be firmly held against the same, forming a tightly closed and hermetically sealed joint for the cap with the article to which it is applied.

It also consists of novel means for conveniently and easily unscrewing the cap from its position.

Figure 1 represents a perspective view of a screw cap embodying my invention. Fig. 2 represents a vertical section thereof, including the adjacent portion of a can to which the cap is applied. Fig. 3 represents a plan view of detached parts.

Similar letters of reference indicate corresponding parts in the figures.

Referring to the drawings:—A designates a screw cap, and B designates the neck of a can or other receptacle to which the same is fitted. On the side of the cap is the inturned bead A', which forms the groove C on the interior of said cap.

D designates a concavo-convex disk of somewhat pliable metal or material, which is placed within the cap A and having its peripheral portion seated in the groove C, said disk owing to its concavo-convex shape being sprung or flexed into said groove, the convex face of the disk being below.

E designates a washer or gasket somewhat of flexible or yielding material preferably linoleum or cork, which is also placed within the cap A and rested against the disk D and sustained by the latter, said gasket being deflected to the contour of the contiguous face of the disk D and also having its peripheral portion sprung into said groove, both disk and gasket thus being firmly retained in the cap. It will now be seen that when the cap is screwed to the neck B, the gasket E contacts with the top edge of the latter and is forced tightly against the disk D, and the latter is subjected to the pressure of said gasket, and so is expanded and tightly seated upon the shoulder formed by the upper wall of the

groove C, said wall thus forming an absolutely tight joint for said cap and neck.

In the side of the cap are openings F, which are preferably opposite to each other and designed to receive a pin or other implement, whereby the cap, otherwise difficult to remove, may be conveniently and easily turned for unscrewing purposes, the effect of which is evident.

It will be noticed that the portion of the interior of the cap above the shoulder C is unoccupied, forming the chamber G, with which the openings F are in communication, and thus the pin or implement, as aforesaid inserted in the openings F, may pass entirely through the interior of the cap, and said pin or implement being adapted to bear simultaneously against the walls of both openings, will not slip from its operative position nor bend or break when in use. It will be noticed also that the cap has a closed top H, the same being flat, whereby it is available for the application of a label lithographed, printed or otherwise produced, and said top may be conveniently cleaned.

While I have specified certain means for carrying out my improvements, I do not wish to be limited exactly to the same, but desire to make such changes as may come within the scope of the novelty involved.

Having thus described my invention, what I claim as new and desire to secure by Letters Patent, is:—

1. A screw cap of the character stated having a groove in the side of the interior thereof, a downwardly convex disk adapted to be peripherally seated in said groove, and a downwardly convex gasket adapted to be sustained on the underside of said disk and having the peripheral portion seated in said groove.

2. A screw cap of the character stated having within the same a disk and a gasket thereunder, said disk being convex on its under face and being adapted to be peripherally seated on a shoulder within the cap, and said gasket being adapted to be sustained on the convex face of said disk, said cap having a closed top, and said side having openings therethrough.

3. A screw cap of the character stated having a body provided with a groove in the inner face of the side thereof, and a downwardly convex disk, and a downwardly convex gasket, both within said body imposed

one upon the other, said groove forming a common seating for the peripheral portions of said gasket and disk.

4. A screw cap consisting of a body composed of a top and a side, the latter having a groove in its inner face, and a gasket and disk in said body, said gasket and disk being imposed one on the other and being downwardly convex, and both having their pe-

ripheral portions seated in said groove, said body having a chamber therein, and an opening in the side, said chamber and opening being above said disk.
